RECIPROCATING MECHANISM FOR
WINDING MACHINES

Peter P. Demay, Downers Grove, Ill.

Original application December 9, 1935, Serial No.
53,446. Divided and this application August
9, 1937, Serial No. 158,160

15 Claims. (Cl. 74—59)

The invention relates to machines embodying reciprocating carriages.

The objects of the invention are to provide reversible gearing for reciprocating a carriage, with improved means for varying the length of the strokes of the carriage; improved controlling means for reversible gearing to more accurately control the length of the strokes of the carriage; improved means for varying the length of the strokes of the carriage in coil-winding machines to wind cores of different lengths, which includes a visual and manually-adjustable indicator for expediting the setting of the machine for carriage strokes of different lengths; and other features which will more fully appear from the detailed description.

The invention consists in the several novel features which are hereinafter set forth and are more particularly defined by claims at the conclusion hereof.

In the drawings: Fig. 1 is a plan, parts being shown in section, of the mechanism for reciprocating the carriage and the controlling mechanism therefor, the carriage being illustrated adjacent its out-stroke. Fig. 2 is a horizontal section illustrating the carriage at the end of its in-stroke. Fig. 3 is a vertical section on line 3—3 of Fig. 1. Fig. 4 is a vertical section on line 4—4 of Fig. 1. Fig. 5 is a section on line 5—5 of Fig. 30 1. Fig. 6 is a vertical section on line 6—6 of Fig. 5. Fig. 7 is a front elevation of the dial and the arms for indicating the position of the carriage and varying its stroke.

The invention is exemplified in a winding machine which comprises a driven arbor 24 which is adapted to receive a core *a* on which coils of wire are to be wound and a reciprocable carriage *b* which carries guide-arms *b'* which carry grooved rollers *b*³ for guiding the wires to the arbor. The machine may be equipped with wire guides for simultaneously winding any desired number of coils on any suitable core or cores on the arbor 25. The machine comprises a supporting base 21 and a housing 22 rigidly secured on 45 the frame or base 21. The carriage *b* comprises a pair of rods *b*², which are slidably mounted in bearings in one end of housing 22. Rods *b*² have their inner ends fixedly secured to a cross-head *b*³.

50 The mechanism for reciprocating the carriage *b* comprises a gear 113 which is fixed to a short shaft 111 which is journaled in a bracket 112 fixed to the base 21. Gear 113 is driven by a gear 156. The latter gear, in practice, is driven by variable speed gearing such as is exemplified

in my patent application filed December 9, 1935, Serial No. 53,446, to vary the speed of travel of the carriage *b* according to the gauge of wire to be wound on the core. A bevel gear 114 is fixed to shaft 111 and provided with a clutch-member 115 provided with radial teeth on its outer face. A bevel gear 118 is journaled on a fixed stud 119 and meshes with bevelled gear 114. A shaft 105 is journaled in a stationary bracket 106 in the housing 22 and a combined radial and thrust bearing 108 in the clutch-member 115. A bevelled gear 116 is loosely mounted on shaft 105, has affixed thereto a toothed clutch-member 117, meshes with bevel-gear 118 and faces the gear 114. A clutch-sleeve 120 is splined to and slidable on shaft 105 and is provided with clutch-teeth at its opposite ends to mesh with the clutch-members 115 and 117, respectively. When the clutch-sleeve 120 is coupled to bevel-gear 114, shaft 105 will be driven in one direction 10 directly from gear 114. When sleeve 120 is disengaged from gear 114 and engaged with clutch-member 117, shaft 105 will be driven in the opposite direction from gear 114 through intermediate idler gear 118 and gear 116. Sleeve 120 is automatically shifted and controlled by mechanism hereinafter described to reciprocate the carriage *b* for the wire-guides. Shaft 105 is secured to a screw 107 which is threaded to a nut 109 which is fixedly held on the cross-head *b*³ and against rotation by a boxing 110 which is secured to said head. The outer end of screw 117 is journaled in a bearing 107^a in a wall of the housing 22. Rotation of the shaft 105 in one direction will cause the screw 107 to rotate in the non-rotatable nut 109 and move the nut 109 and the carriage *b* in one direction and reverse rotation of shaft 105 will rotate screw 107 to move the nut 109 and the carriage *b* longitudinally in the reverse direction.

40 The machine includes mechanism for automatically shifting the clutch-sleeve 120 to impart strokes of different lengths to the carriage *b* for winding coils of different lengths. This mechanism comprises a transverse shaft 175^a 45 which is journaled in a bracket 175^a fixed on the base 21, and gearing for driving said shaft in opposite directions and in accordance with the shaft 105 which operates the screw 107. Said gearing comprises a worm 171 fixed to shaft 105, a worm gear 172 engaged by said worm and fixed to a shaft 172^a which is journaled in upstanding lugs on bracket 106, a pinion 173 fixed to shaft 172; a gear 174 fixed to shaft 175 and meshing with pinion 173.

A shifter collar 183 is adapted to slide clutch-sleeve 120 into engagement with either of the gears 114, 116 to drive shaft 105 and screw 107 in opposite directions. A lever 184 for shifting collar 183 is fulcrumed at 185 to swing horizontally and is provided at its outer end with an abutment plate 186. An abutment-arm 205, controlled by a rotatable cam 182 on shaft 175 and an abutment arm 204 controlled by a cam 181 also rotatable with said shaft, control the movements of lever 184 and clutch-sleeve 120 at the ends of the in and out-strokes of the carriage *b* to lock the clutch-sleeve in its engaged positions during the strokes of the carriage. These abutment arms alternately lock and release said lever under control of said cams. Adjustable stops 201 are provided to limit the travel of lever 184.

Cam 182 is fixed on a hub which is fixed to shaft 175. Cam 182 is adapted to engage an arm 206 on a rocker 202^a to which abutment arm 205 is fixed. Cam 181 is fixed on a clutch-member 177 and is adapted to engage an arm 208 on rocker 202^a which is loose on a shaft 202^b. This shaft extends through rocker 202^a and abutment arm 204 is fixed to said shaft. An arm adapted to be struck by cam 181 is fixed to shaft 202^a. A spring 210 is applied to an extension on arm 205 to press arm 206 towards the face of cam 182 and arm 205 against the outer face of the abutment-plate 186 when the arm 205 is held by the outer edge of said plate. A spring 211 is applied to an extension on arm 204 to rock arm 208 toward cam 181 and to hold arm 204 against the outer edge of abutment-plate 186 when the latter arm is arrested by said outer edge. Shaft 202^b is journaled in brackets 203.

The invention provides for readily varying the strokes of the carriage by rotatably adjusting cam 181 relatively to cam 182 to vary the timing of the periods of engagement of clutch-sleeve 120 with gears 114, 116, respectively. An index-arm 212 is keyed to and rotates with shaft 175 and cam 182 and moves around a dial 214 on the front of a head 179 fixed in the front of housing 22. This index arm follows the movement of the cam 182 and indicates its position. A nut 213 holds the index-arm 212 on the front end of shaft 175. An index-arm 180 is fixed to rotate with a sleeve 178 which extends around shaft 175 and is journaled in head 179. Sleeve 178 is pinned to clutch-member 177. A spring 215 is adapted to press clutch-members 176, 177 apart when the nut 213 is loosened or removed from the front end of shaft 175 to permit index-arm 180 to rotatably adjust clutch-member 177 with its cam 181 to vary the arc of travel between cam 181 and arm 208. The spacing between index arms 180 and 212 and corresponding spacing between cams 182 and 183 will control the lengths of the strokes of carriage *b*. When a change in the length of the stroke is desired, the operator will loosen nut 213 so that index-arm 180 which is fixedly connected to clutch-member 177 which carries cam 181 can be rotated relatively to its coating clutch-member 176 to effect a different setting between the index arms and a corresponding variation in the periods between the movements of the clutch-sleeve 120 of the reverse gearing for reciprocating the carriage. The rotative adjustment of cam 181 relatively to the arm 208 engaged thereby varies the length of the strokes of the carriage to adapt the machine for winding coils of different lengths. During the

operation of the machine, index arms 180, 212 rotate together and the graduations between said arms indicate the length of the carriage stroke for which the machine is set. This exemplifies means which is easily, quickly and accurately adjustable to vary the length of the carriage strokes for winding coils of different lengths.

A pair of rods 187 are adjustably secured to projecting lugs on shifter collar 183; are slidable in and through bracket 106 and are cross-connected by a bar 188. Springs 189 are applied between bracket 106 and collars 189^a which are shouldered against and slidable on rods 187 and in the cross-bar 188 to exert pressure to the rod on cross-bar 188 to engage and shift, through rods 187, the collar 183 so that sleeve 120 will engage bevel-gear 116 when the controlling lever 184 is released by arm 204, as the result of the cam 181 shifting arm 206, shaft 202^b and arm 204. This occurs at the end of each out-stroke of the carriage *b* and the points at which the out-stroke terminates and the in-stroke begins are variable by the rotative adjustment of cam 181 and clutch-member 177, as before described. This constitutes index-controlled mechanism for varying the lengths of the strokes of the reciprocating carriage.

Collar 183 is reversely shifted for engaging sleeve 120 and bevel-gear 116 at the end of each in-stroke of the carriage by a pair of abutment-collars 200^a which are fixed on rods 200. The outer ends or rods 200 are fixedly secured in cross-head *b*³ so they will reciprocate with the carriage and their inner portions are slidable through collars 189^a in cross-bar 188. The inner ends of rods 200 are slidable in bracket 106. Washers 190^a are slidable on rods 200 and are pressed against collars 200^a by springs 190 which are interposed between said washers and the cross-head *b*³. During the in-stroke of cross-head *b*³ collars 200^a engage the collars 189^a and relieve the cross-bar 188 from the pressure of springs 189. Thereafter the spring-pressed washers 190^a engage the cross-bar 188 to apply the pressure of springs 190 to said cross-bar to cause the collar 183 to be shifted to the left as soon as lever 184 is released by arm 205 under control of the cam 182 and arm 205. This spring-pressed means for shifting the clutch-sleeve of the reversible gearing at the end of the in-stroke of the carriage exemplifies a construction by which spring-pressure will be applied to the sleeve before the controlling mechanism releases the lever 184 for its respective movements for a quick and accurate timing of clutch-sleeve 120 in the reciprocations of carriage *b*.

The operation of the machine will be as follows: the operator will place a core of any suitable type on the arbor 24. The ends of the wires from the supply reels will then be directed around the guide-sheaves *b*³ and secured on the core. The operator will set the indicator arms 180 on the dial 214 and relatively to the index 212 to correspond to the length of the coils desired. In this setting, cam 181 will be rotatably adjusted to its arm 208 to vary the timing or periods between the shifting movements of clutch-sleeve 120 of the reverse gearing for reciprocating the guide-carriage. After the setting has been made, nut 213 will be tightened to fix clutch-members 176, 177 together to fix the relative rotative spacing between cams 181 and 182. This will result in varying the length of the carriage strokes. Assuming the carriage *b* to be approaching the

end of its out-stroke, as illustrated in Fig. 1, cam 181 will engage arm 208 at the desired point. The cam will rock arm 208, shaft 202^b and arm 204 against the force of spring 211. Arm 204 will be moved outwardly to release abutment 186 on lever 184, whereupon the force of springs 189 will be applied through cross-bar 188 and rods 187 to collar 183 to instantaneously shift sleeve 120 into engagement with gear 116 to start the in-stroke of the carriage. As soon as the lever 184 is shifted, spring 210 will rock arm 205, rocker 202^a and arm 206 to cause arm 205 to move toward the fulcrum of lever 184 and into position to lock abutment plate 186 on said lever in position to keep sleeve 120 coupled to gear 116 during the in-stroke of the carriage caused by the reversal of shaft 105 and screw 107. When the carriage 5 approaches the end of its in-stroke, the mechanism for shifting the collar 183 will be in position illustrated in Fig. 2. At such time collars 200^a will have engaged spring-pressed sleeves 189 to disengage the collars from cross-bar 188 and washers 190^a will be pressed against cross-bar 128 by springs 190 to force the cross-bar and rods 187 inwardly to shift clutch-collar 183 and sleeve 120 into engagement with gear 114 as soon as lever 184 is released by arm 205. This release of arm 205 occurs when cam 182 strikes arm 206 and thereby rocks arm 205 into position shown in Fig. 1. When arm 205 is thus rocked, lever 184 will be shifted by the force of springs 189 to couple sleeve 120 with gear 114 and arm 205 will then rest against the outer edge of abutment-plate 186 and be held against retraction by said plate during the out-stroke of the carriage. At the end of the in-stroke of the carriage, arm 204 will be held by abutment-plate 186 while the latter is locked against pivotal movement by arm 205 until the end of the out-stroke of the carriage.

This application is a division of an application filed by me December 9, 1935, Serial No. 53,446.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In mechanism for reciprocating a carriage, the combination of reversible clutch mechanism, a rotatable element driven by said mechanism and connected to reciprocate the carriage, and mechanism for controlling the clutch mechanism comprising a pair of rotatable cams driven from said mechanism, a clutch for driving one of the cams and means for setting the latter clutch to rotatably adjust one cam relatively to the other for varying the length of the strokes of the carriage.

2. In mechanism for reciprocating a carriage, the combination of reversible clutch mechanism, a rotatable element driven by said mechanism and connected to reciprocate the carriage, and mechanism for controlling the clutch mechanism comprising a rotatable cam, a clutch for driving the cam speed-reducing gearing for driving the clutch from said element, and means for resetting the latter clutch to adjust the cam for varying the length of the strokes of the carriage.

3. In mechanism for reciprocating a carriage, the combination of reversible clutch mechanism, a rotatable element driven by said mechanism

and connected to reciprocate the carriage, and mechanism for controlling the clutch mechanism comprising a shaft, gearing driven by the element for driving the shaft, a pair of cams mounted on and to rotate with the shaft, a rock-shaft 5 and means on the rock-shaft operable in opposite directions by the cams, respectively.

4. In mechanism for reciprocating a carriage, the combination of a reversible clutch mechanism, a rotatable element driven by said mechanism and connected to reciprocate the carriage, and mechanism for controlling the clutch mechanism comprising rotatable cams driven from said element, and spring-means for engaging the clutch mechanism under control of the cams. 10

5. In mechanism for reciprocating a carriage, the combination of a reversible clutch mechanism, a rotatable element driven by said mechanism and connected to reciprocate the carriage, and mechanism for controlling the clutch mechanism comprising rotatable cams driven from said element, spring-means for engaging the clutch mechanism under control of the cams, and means for adjusting one of the cams to vary the length 20 of the strokes of the carriage. 25

6. In mechanism for reciprocating a carriage, the combination of reversible clutch mechanism, a rotatable element driven by said mechanism and connected to reciprocate the carriage, and mechanism for controlling the clutch mechanism comprising locking-means for the clutch mechanism, spring-means for engaging the clutch mechanism and rotatable cams driven by said mechanism for releasing the locking-means. 30

7. In mechanism for reciprocating a carriage, the combination of reversible clutch mechanism, a rotatable element driven by said mechanism and connected to reciprocate the carriage, and mechanism for controlling the clutch mechanism comprising locking-means for the clutch mechanism, spring-means for engaging the clutch mechanism, rotatable cams driven from said element for releasing the locking-means, the friction-clutch for driving one of the cams and means for adjusting the friction clutch to set the clutch 40 driven cam to vary the length of the strokes of the carriage. 45

8. In mechanism for reciprocating a carriage, the combination of reversible clutch mechanism, a rotatable element driven by said mechanism and connected to reciprocate the carriage, and mechanism for controlling the clutch mechanism comprising rotatable cams, gearing for rotating the cams from said element, one of said cams being adjustable, and an indicator comprising an 50 index connected to set the adjustable cam to vary the length of the strokes of the carriage. 55

9. In mechanism for reciprocating a carriage, the combination of reversible clutch mechanism, a rotatable element driven by said mechanism and connected to reciprocate the carriage, and mechanism for controlling the clutch mechanism comprising rotatable cams, gearing for rotating the cams from said element, an indicator comprising an index, and a clutch between the index 60 and one of the cams, comprising a member whereby the other cam can be set to vary the length of the strokes of the carriage. 65

10. In mechanism for reciprocating a carriage, the combination of reversible clutch mechanism, a rotatable element driven by said mechanism and connected to reciprocate the carriage, and mechanism for controlling the clutch mechanism comprising rotatable cams, gearing for rotating the cams from said element, one of said cams 70

75

being adjustable, and an indicator comprising a pair of index arms connected to move with the cams, respectively, one of the cams being adjustable to vary the length of the strokes of the carriage.

11. In mechanism for reciprocating a carriage, the combination of reversible clutch mechanism, a rotatable element driven by said mechanism and connected to reciprocate the carriage, and mechanism for controlling the clutch mechanism comprising a centrally fulcrumed lever having one of its ends connected to shift the clutch mechanism and its other end extended to form an abutment, spring-pressed arms adapted to swing to the sides of the abutment, respectively, to lock the lever and clutch mechanism in its alternative positions, and means for shifting said arms to release the lever, comprising rotatable cams driven from said element.
12. In mechanism for reciprocating a carriage, the combination of reversible clutch mechanism comprising a clutch-sleeve, a rotary element driven by said mechanism and connected to reciprocate the carriage, and mechanism for controlling the clutch mechanism to control the length of the strokes of the carriage, comprising a slideable rod connected to the sleeve, spring-means for shifting the rod to shift the sleeve into one of its alternative positions, a second rod secured to move constantly and reciprocate with the carriage, means on said second rod for disengaging the spring-means from the first mentioned rod, spring-pressed means on said second rod for shifting the first-mentioned rod to shift the sleeve into its other position, and means for locking and releasing the sleeve in its alternative positions.
13. In mechanism for reciprocating a carriage, the combination of reversible clutch mechanism, comprising a clutch-sleeve, a rotary element driven by said mechanism and connected to reciprocate the carriage, and mechanism for controlling the clutch mechanism to control the length of the strokes of the carriage, comprising a slideable rod connected to the sleeve, a second rod secured to move constantly and reciprocate with the carriage, spring-means for shifting the rod to shift the sleeve into one of its alternative positions, an element secured to move constantly

and reciprocate with the carriage, means on said second rod for disengaging the spring-means from the first-mentioned rod, and spring-pressed means on said second rod for shifting the first-mentioned rod to shift the sleeve into its other position, and means for locking and releasing the sleeve in its alternative positions.

14. In mechanism for reciprocating a carriage, the combination of reversible clutch mechanism, comprising a sleeve, a rotary element driven by said mechanism and connected to reciprocate the carriage, and mechanism for controlling the clutch mechanism to control the length of the strokes of the carriage comprising a pair of rods slidably mounted in a stationary support and connected to the sleeve, a cross-bar connecting the rods, spring-means applied to the cross-bar for shifting the rods to shift the sleeve into one of its alternative positions, a pair of rods secured to move constantly and reciprocate with the carriage, collars on the latter rods adapted to engage the spring-means to disengage the spring-means from the cross-bar, and spring-pressed elements on the rods movable with the carriage for shifting the cross-bar to shift the sleeve into its other position.

15. In mechanism for reciprocating a carriage, the combination of reversible clutch mechanism comprising a clutch-sleeve, a rotary element driven by said mechanism and connected to reciprocate the carriage, and mechanism for controlling the clutch mechanism to control the length of the strokes of the carriage comprising a pair of rods slidably mounted in a stationary support and connected to the sleeve, a cross-bar connecting the rods, spring-means comprising collars engaging and for shifting the cross-bar to shift the sleeve into one of its alternative positions, a second pair of rods secured to move constantly and reciprocate with the carriage, and extending through the spring-means, collars on the second pair of rods adapted to engage the spring-means to disengage the spring-means from the cross-bar, and spring-pressed elements on the rods movable with the carriage for shifting the cross-bar to shift the sleeve into its other position.

PETER P. DEMAY.
